UNITED STATES PATENT OFFICE

ANNIBALE A. GUERINI, OF NEW YORK, N. Y.

MECHANICAL BRICKLAYER DEVICE

Application filed September 29, 1927. Serial No. 222,828.

My invention consists of a mechanical device which may be employed for setting bricks in a wall.

The object of the invention consists in a device composed of four parts, by which it is possible to divide the work of the bricklayer into several specialized parts, and have each man perform his own special work in order to obtain more efficient and perfect work.

10 The accompanying drawings illustrate one practical embodiment of the invention, but the device therein shown is to be understood as illustrative, only, and not as defining the limits of the invention.

15 Figure 1 is a top view of a wall showing the four parts of the device set in position.

Figure 2 is a side view of Figure 1.

Figures 3 and 4 and 6 are sections of the wall and associated devices. These sections 20 are taken on the lines 3—3, 4—4 and 6—6 of Figures 1 and 2.

Figure 5 is an enlarged fragmental section of a wall with the pattern for laying the bricks shown in section on the line 5—5 of 25 Figures 1, 2 and 7.

Figure 7 is a top view of the pattern on enlarged scale.

Figures 8 and 10 are detail views of the transverse bars of the pattern.

30 Figure 9 is a view of the inside longitudinal bars of the pattern.

Figure 11 is a top view of a wall showing an opening and one corner of the wall, with the patterns for laying bricks set in position.

35 Figure 12 is a front view of a flat arch.

Figure 13 is a front view on enlarged scale showing a flat arch.

Figure 14 is a top view of the truck for the dropping hammer.

40 Figure 15 is a longitudinal section on the line 15—15 of Figure 14.

Figure 16 is a longitudinal section on the line 16—16 of Figure 15.

The mechanical bricklayer which is illustrated in the accompany drawings is made for building walls with sunken joints and embodies four parts, viz: E is the frame for laying the mortar, and is formed by the two sides 1 and 2 and the two heads 3 and 4. The 50 outside faces of the two sides are made to

come flush to the face of the wall, and the sides have a thickness equal to the depth of the sunken joints. The height of the sides is a trifle more than the thickness of the joints, which are brought afterwards to the desired thickness, by the action of the hammer over the layed bricks as hereinafter described. The frame is adapted to be held firmly in position by tongues 5, secured in each side thereof. The lower end of the tongues flare outwardly to facilitate the setting of the frame. The two heads 3 and 4 have the same outline as the heads of the pattern F, and the several segments of each head are secured together by screws, so as to make the frame rigid and at the same time easy to dismantle and reassemble when it is desired to change the outside lines.

The pattern F has the same outline as the frame E, with the difference that the inside part of the two sides 6 and 7 are adapted to be flush with the wall. The pattern is composed of the longitudinal bars 6, 7, 8, 9 and 10 and the transverse bars 11 and 64. The number of the longitudinal and the transverse bars will vary in accordance with the thickness of the wall and the position which the bricks are to be laid.

The thickness of the inside longitudinal bars 8, 9 and 10 and the transverse bars 11 and 64 is a trifle less than the joints to be formed between bricks, and the bars are set apart in accordance with the size of the brick. The inside longitudinal and the transverse bars are of slightly less height than the outside longitudinal bars, so that they will be free from contact with the mortar below. At one end of the two outside longitudinal bars 6 and 7, see Figure 7, are secured the ears 1 and 13 provided with holes for the pins 14 and 15, and at the opposite end, these bars have two holes 16 and 17. The ears, the pins and the holes serve to connect the patterns together, when several patterns are set in position end to end in a continuous line.

Near the ends and in both of the outside longitudinal bars are secured the braces 18 and 19, see Figure 5. On the lower end of these braces 18 and 19 are fixed the plates 20.

The inside faces of the plates and braces are in vertical alinement with the inside faces of the outside longitudinal bars 6 and 7. About midway of its length each of these braces is provided with a threaded hole for a threaded pin 21. The location of this pin must be accurately fixed, by calculating the thickness of the bricks to be used and the width of the joints to be allowed. A small error in the location of this pin is bound to result in error in the height of the openings for doors and windows. Each pin 21 has an adjustable collar 22 adapted to be locked in position by a set screw so as to prevent the pins from entering into the joints more than it is desired.

In the top of the outside longitudinal bars 6 and 7 are holes 23 for hooks 24 fixed in the transverse bars 11 and 64. Whenever the transverse bars 11 and 64 are part of the heads of the pattern, these bars, beside being hung to the longitudinal bars, are also secured to them by screws, the screws to be used for this purpose being the thumb screws 25. When securing the ears 12 and 13, the braces 18 and 19 and the thumb screws 25 to the bars, care should be taken that they will not interfere with the flange of the wheels of the truck for the dropping hammer, presently to be described.

In the top of the inside longitudinal bars are also vertical holes 23, see Figures 8, 9 and 10. The top part of each hole is cut to form a channel and this channel will permit the hook of the transverse bars to descend until the top surface of the transverse bars are flush with the top surfaces of all longitudinal bars. Below the vertical holes 23 are the threaded holes 26, these holes are at the same distance from the top surface of the bars as are the holes 27 of the transverse bars. The transverse bars are of two dimensions, the bars 11 are a trifle longer than the width of the brick, and the bars 64 are a trifle longer than the length of the brick. The section of the transverse bars is the same as the inside longitudinal bars, and on their ends are fixed the hooks 24 adjacent holes 27. The hooks are used for connecting the transverse bars to the longitudinal bars. The pattern is made rigid by tightening the screws 25.

The outside line of the grouting frame G is the same as the mortar layer frame E, and to this grouting frame are secured the teeth 29. The inside faces of the teeth are flush with the inside face of the longitudinal bars 30. The width of the teeth is a trifle less than the width of the joints, and each tooth a trifle less in height than the thickness of the bricks. The teeth must be accurately positioned on the transverse bars of the pattern. The purpose of the teeth is to close the opening of the joints at the fixed depth.

The truck for the dropping hammer is adapted to run on top of the outside longi-

tudinal bars of the patterns. The frame of the truck is composed of the two horizontal bars 31 and 32 to which are bolted the inclined bars 33 and 34 and the transverse bar 35. At the front of the frame is secured the casing 36 for the dropping hammer 27. To the under part of the horizontal bars are secured the bearings for the shafts 38, 39, 40 and 41. The shaft 38 is composed of three parts and these three parts are united by the couplings 42 and 43. By dividing this shaft in three parts, it is possible to use the truck for building walls of different thickness. The truck is made adjustable for this purpose by lengthening the parts of the shaft to which are secured the flanged wheels 44 and 45, and by lengthening the two shafts to which are secured the flanged wheels 46 and 47.

On the shaft 38 is fixed a gear 48 which drives a gear 49 secured on the shaft 39. On shaft 39 are fixed the toothed wheels 50 and 51. When rotated, the teeth 52 of these wheels will engage lugs 53 fixed to the hammer 37, and will raise the hammer, and as soon as the teeth are released from the lugs, the hammer will drop. In the opposite ends of the hammer casing are openings 54 in which move the bars 55 of the hammer. Across these openings are secured the stops 56, the purpose of which is to prevent the hammer from striking the longitudinal bars after the bricks are driven down to a point at which the top faces of the bricks are substantially flush with the top faces of the bars. In the rear of the casing are slots in which the lugs 53 operate. The truck is moved by a handle 57 which is secured to the shaft 38.

The pattern for building the arches is composed of thin strips 58, to which are fixed channels 59 (Figures 12 and 13). The strips are laid on top and secured to the wooden form 60 below. In the channels are inserted the bars 61 which have a thickness equal to the width of the joints. If the bricks for the construction of the arch are of conventional size, the bars 61 must be narrow at the bottom and wide on top, but if the bricks are made to the radius of the arch, then the bars 61 are about of the same thickness throughout their length. The tops of the bars 61 enter in channels 62 fixed to the strips 63. The positions of the channels must, of course, be in accordance with the radius of the arch.

In order to get the best results through the use of the apparatus of this invention, it is necessary to have the bricks in such condition that they may be handled rapidly so as not to delay the work for the preparation of bricks. I find it desirable, in practice, to prepare a number of bricks before starting the work. That is to say, in building some walls it is necessary to use half brick lengths.

A number of such half brick lengths should be provided so that they are ready at hand. The cutting of the bricks may be accomplished by machines well known to the trade and forms no part to this invention.

5 Ordinarily the work of building a wall is carried on by one or more men, each of which men are assigned to a particular portion of the wall and each man places his own particular part of the wall. In accordance with the present invention, in contradistinction, the several men who are engaged in building the wall with the apparatus of this invention operate conjointly upon the work to be done and cooperate in the use of the apparatus so that the several courses are built up throughout the length of the wall by the use of the machine as carried on by a gang of men which manipulate it.

20 In practice, the apparatus may be operated with such rapidity that the highest efficiency generally demands about six men. For example, the work is started by the mortar man whose duty it is to set one or 25 more mortar frames E end to end along the line of the wall. For the first few courses the downward projections of the mortar frames as well as the patterns which are subsequently used should be removed until 30 the wall is at a sufficient height to permit these projections to be used. Considerable care should be exercised in laying the first few courses of brick as an error made in these courses will be repeated throughout 35 the wall.

After one or more of the frames are set in position, mortar is dumped upon the frame and fills in the confines of the frame. The mortar is smoothed off at the top of the frame by the use of a straight edge and the frame may then be removed and placed at the end of the row of frames which is being set up. As soon as the mortar frame is removed from the mortar, the man in charge of the pattern frame sets the pattern right on top of the mortar layer being careful to note that the pins 21 enter into the predetermined joint and these pins are then turned up tight against the collars and the four thumb screws 40 are tightened. During this work, it is desirable in practice to use three patterns at a time positioned end to end. This minimizes errors in length and vertical and horizontal levels. At the same time as the second or pattern man is setting the pattern, the first man 45 will have laid another batch of mortar so that the pattern man can set additional patterns as he removes them from their previous position. The consecutive patterns are 50 connected by the pins 14 and 15. If these pins do not properly fit in the holes of adjacent patterns, it will be apparent at once that the pattern is not being set correctly and appropriate correction may be made.

55 As the pattern man finishes setting the pat-

tern, the brick man fills the pattern with bricks received from a hod carrier or wheelbarrow man in order that the bricks may be quickly and expeditiously supplied to the brick layer. The hammer apparatus is preferably operated by another man whose duty 70 it is to attend to this machine exclusively. As soon as the patterns are filled with bricks, the hammer man sets the truck carrying the hammer on the top of the pattern with the flange 75 wheels run on the outside longitudinal bars thereof. The truck is run back and forth until the bricks 65 (see Figure 5) which project above the patterns are depressed by blows of the reciprocating hammer until they 80 become flush with the top faces of the bars.

After the bricks are properly tamped or hammered into place as specified by the hammer apparatus, this apparatus is moved on to the next pattern and immediately the pattern which has just been finished is removed and placed on the forward end of the row which is being built up. The grouting frame is next set over the bricks just laid. A separate man preferably handles this work. He 85 sets the grouting frame over the hammered bricks and makes sure that the teeth 29 enter the transverse joints of the bricks so as to give proper depth to the joints. After a grouting frame is in position, a quantity of 90 grout is dumped into the frame and with the help of a trowel or scraper, the grout is caused to sink into the joints between the bricks. The grout is preferably fairly stiff so that as 95 soon as it has been placed in position the grout frame can be removed and set into another section further along.

It will thus be apparent that when several men are working along the same course and operating the several parts of the apparatus, the work proceeds very rapidly and at the same time with mechanical uniformity. In practice, the speed with which the bricks can be laid by this apparatus is greatly in excess of that at which even the best brick layer can lay them and work is moreover more uniform than could be done by hand. Furthermore, skilled bricklayers are not required to do the work as relatively unskilled labor has been found to give thoroughly satisfactory results.

At the end of each course, it is necessary to have the patterns set for the next course so the bricks of the next course are laid across the joints below. This operation is easily accomplished. The transverse bars are unhooked, the head bars are unscrewed from the longitudinal bars, and the new compartments of the pattern will be assembled so that the transverse bars will be in the center of the bricks below. Whenever the courses are made with the bricks on end the inside longitudinal bars are reduced in quantity and the short transverse bars 11 are substituted with the transverse bars 64. However, as the sets of frames and patterns are not very expen-

sive, it is practical to have a few sets for each different course. The set of patterns for the corners and openings are made expressly for the purpose.

- 5 In Figure 11, a wall in the making is shown and in this view a number of patterns are in position to receive the bricks. In most of these patterns, the bricks have been placed while in one of them, the bricks are omitted. 10 The section H corresponds to a solid portion of the wall, while the section L corresponds to an opening such as a door or window opening. There are no bricks in this section, but the pattern has been incorporated in order 15 that proper spacing of the patterns for the sections H and M may be obtained. Furthermore, certain bricks have been omitted at the adjacent ends of the sections H and M so as to form jambs at the opening. The section 20 N shows corner construction and as here illustrated, these corner patterns are especially made for the purpose and the compartments therein are appropriate to particular courses. It will be apparent, however, that 25 special corner sections are not essential and that the corners may be set by the use of the regular wall molds.

For the building of an arch, straight or curved, the pattern is composed of a lower 30 strip 58 which is set on top the form 60, and the bars 61 which are inserted in the channels 59 and 62. The bars are a trifle wider than the interior joint of the bricks, so that one bar will support the edges of two bricks. The 35 bricks are laid over the bars, starting from the two sides toward the center. After the bricks are laid, the joints are filled with grout and when the grout has started to set, the top strip 63 is removed and the bars 61 40 are pulled up. The holes left by the bars are filled with grout.

From the above description, it is evident that in building a wall with the mechanical bricklayer, it is not necessary to have skilled 45 and experienced bricklayers, as the responsibility for accuracy rests on the architect who provides the plans. By using the mechanical bricklayer, the walls are built more accurately than is possible when the bricks are 50 laid by hand as heretofore. Moreover, the joints will be all filled. Besides the above advantages, the mechanical bricklayer affords a saving of labor, as there is no loss of 55 time in plumbing or aligning as when the work is done by hand.

Having thus fully described the invention, what I claim as new and desire to secure by Letters Patent is:

1. In a mechanical bricklayer, a pattern divided into compartments shaped to receive the bricks to be laid and suitably disposed to produce a staggered relation between the respective bricks, and means for maintaining the pattern in horizontal position on a wall 60 and against inadvertent movement in a di-

rection perpendicular to the face of the wall, said means comprising a plurality of supporting projections carried by the pattern and arranged to extend into the joints between previously laid courses of bricks to support the pattern in firm position directly upon an already built portion of the wall. 70

2. In a mechanical bricklayer, a pattern divided into compartments shaped to receive the bricks to be laid and suitably disposed to produce a staggered relation between the respective bricks, and means for supporting the pattern in horizontal position on a wall and at a predetermined distance from the next subjacent course of bricks, said means comprising a plurality of supporting projections carried by the pattern and arranged to extend into joints between previously laid courses of bricks to support the pattern in firm position directly upon an already built portion of the wall. 75

3. In a mechanical bricklayer, a pattern embodying a plurality of compartments adapted to receive bricks and space them apart in predetermined relation, and means for supporting the pattern in horizontal position on a wall and in desired vertical spaced relation above the next subjacent course of bricks in the wall, said means comprising a plurality of supporting projections carried by the pattern and arranged to extend into joints between previously laid courses of bricks to support the pattern in firm position directly upon an already built portion of the wall. 80

4. In a mechanical bricklayer, a pattern embodying a plurality of longitudinally extending bars with spacing elements positioned between the bars to space said bars apart and form therewith a plurality of compartments adapted to receive bricks in predetermined spaced apart relation, means for detachably securing the longitudinal bars and transverse spacing elements rigidly together, and means for supporting the pattern in predetermined relation to the preceding courses of brick in a partially built wall. 95

5. In a mechanical bricklayer, a pattern embodying a plurality of longitudinally extending bars with spacing elements positioned between the bars to space said bars apart and form therewith a plurality of compartments adapted to receive bricks in predetermined spaced apart relation, means for detachably securing the longitudinal bars and transverse spacing elements rigidly together, means for supporting the pattern in predetermined relation to the preceding courses of brick in a partially built wall, and brick setting mechanism embodying a wheeled truck adapted to ride on the longitudinal bars of the pattern, and brick setting means carried by said truck and operable upon bricks contained in the compartments 110 115 120 125 130

to set the bricks into a bed of mortar provided beneath them.

6. In a mechanical bricklayer, a pattern embodying compartments in which bricks are adapted to be positioned, means for supporting the pattern in horizontal position above a bed of mortar, and a reciprocating hammer supported on the pattern and operable upon the bricks to drive the bricks down to a proper seat in the mortar bed.

10 7. In a mechanical bricklayer, a pattern embodying compartments in which bricks are adapted to be positioned, means for supporting the pattern in horizontal position above a bed of mortar, a wheeled carriage mounted to traverse the top of the pattern, and hammering mechanism on said carriage to hammer the bricks contained in the pattern to a proper seat in the bed of mortar.

20 8. In an apparatus of the character described, a pattern embodying longitudinal bars spaced apart by spacing elements which form with the bars compartments adapted to receive bricks in predetermined spaced apart relation, and means for detachably securing the spacing elements to the bars, whereby the parts may be dismantled and re-assembled to vary the relation between the compartments.

30 9. In an apparatus of the character described, a pattern embodying longitudinal bars spaced apart by spacing elements which form with the bars compartments adapted to receive bricks in predetermined spaced apart relation, means for detachably securing the spacing elements to the bars, whereby the parts may be dismantled and reassembled to vary the relation between the compartments, and means for supporting the pattern in horizontal position above a partially built wall.

40 10. In an assembly of the character described, a pattern embodying a plurality of compartments adapted to receive bricks, and means for supporting the pattern in horizontal position on a partially built wall and in predetermined spaced relation above the next preceding course of previously laid bricks, said means comprising a plurality of supporting projections carried by the pattern and arranged to extend into joints between previously laid courses of bricks to support the pattern in firm position directly upon an already built portion of the wall.

50 11. In an assembly of the character described, a pattern embodying a plurality of compartments adapted to receive bricks, and supporting devices secured to the pattern for supporting the pattern on a wall in level horizontal position and at a predetermined distance above a previously laid course of brick and in correct, lateral adjustment to insure vertical building of the wall said means comprising a plurality of supporting projections carried by the pattern and arranged to

extend into the joints between previously laid courses of bricks to support the pattern in firm position directly upon an already built portion of the wall.
